UNITED STATES PATENT OFFICE.

HELENE LYONS LONG, OF SPOKANE, WASHINGTON.

DESIGN FOR A COMBINED SMOKER'S OUTFIT AND RECEPTACLE FOR GAME ACCESSORIES.

Application filed June 12, 1928. Serial No. 27,093. Term of patent 7 years.

To all whom it may concern:

Be it known that I, HELENE LYONS LONG, a citizen of the United States, residing at Spokane, county of Spokane, and State of Washington, have invented a new, original, and ornamental Design for a Combined Smoker's Outfit and Receptacle for Game Accessories, of which the following is a specification, reference being had to the accompanying drawing, forming a part thereof.

The figure is a perspective view of a combined smoker's outfit and receptacle for game accessories.

I claim:

The ornamental design for a combined smoker's outfit and receptacle for game accessories, as shown.

HELENE LYONS LONG.
